UNITED STATES PATENT OFFICE.

EDGAR G. HAMILTON, OF BURLINGTON, VERMONT.

MAILING-TUBE.

969,367.

Specification of Letters Patent. Patented Sept. 6, 1910.

Application filed August 6, 1907. Serial No. 327,328.

To all whom it may concern:

Be it known that I, EDGAR G. HAMILTON, a citizen of the United States, residing at Burlington, in the county of Chittenden 5 and State of Vermont, have invented certain new and useful Improvements in Mailing-Tubes, of which the following is a specification, reference being had therein to the accompanying drawing.

10 My invention relates to improvements in mailing tubes.

The object of my invention is to provide a tube which is so constructed and arranged that the contents thereof may be readily removed and the tube at the same time maintaining the same advantages of the ordinary tube.

Another object of my invention is to provide a more simple cheap and effective tube 20 to accomplish the above results.

In the accompanying drawings Figure 1 is a perspective view of my improved tube. Fig. 2 is a view similar to Fig. 1 showing the contents of the tube in a position to be 25 grasped for removal. Fig. 3 is a perspective view of one end of a tube showing a modified form. Fig. 4 is a perspective view of Fig. 3 showing the contents of the tube in a position to be grasped for removal. Fig. 5 is a perspective view of a still further modification showing at the left end an opening and at right hand end a single longitudinal slit.

Referring now to the drawings 1 represents a tube which is of the ordinary form made of paper or paste-board and formed either by spiral winding or by winding an oblong sheet of paper or in any other manner as this forms no part of my invention.

40 The tube 1 adjacent one end is provided with a transverse slit 2 which leaves a solid portion 3 between said slit and the end 4 of the tube. The said transverse slit or cut 2 extends approximately half way around the 45 tube which makes the manipulation of the tube more easy but could if desired be made slightly shorter.

The roll of papers or drawings as indicated are placed in the tube the same as the 50 ordinary plain tube and the tube wrapped in the usual manner for mailing. When it is desired to remove the contents of the

tube the wrapper is removed and by pressing down upon the tube on the inside of the slit or cut as indicated at 6 the tube can be 55 depressed inwardly and carrying with it the contents of the tube, thus forcing the contents thereof away from one wall of the tube. The portion 3 of the tube between the slit 2 and end 4 remaining in its normal 60 position allows the finger to grasp the contents of the tube and remove the same and also serves as a solid end for the tube to form a solid tube and prevent the contents of the same from being mashed or otherwise 65 injured.

In Figs. 3 and 4 I have shown two longitudinal parallel slits 7 and 8 a distance from the end of the tube and the material of the tube between said slits can be depressed as 70 indicated at 9 in Fig. 4 which forces the contents of the roll inwardly the same as described in respect to Fig. 1 and the drawings can be removed.

In Fig. 5 on the left I have shown the 75 tube provided with an elongated opening 10 and the contents of the tube can be forced inwardly by a direct engagement thereof by the finger as will be readily seen. On the right of Fig. 5 I have shown a single slit or 80 cut 11 extending longitudinally of the tube and the same can be pressed inwardly on either side of the slit for forcing the contents of the tube away from the walls thereof.

Having thus described my invention what I claim and desire to secure by Letters Patent is:—

An article of manufacture, comprising a tube having a transverse weakened portion 90 intermediate its ends and spaced a distance from one end, said weakened portion extending a distance around the periphery of the roll to allow the contents to be forced away from the side of the tube and said weakened 95 portion of such a length that the full inward movement thereof will not injure the contents of the roll.

In testimony whereof I do affix my signature in presence of two witnesses.

EDGAR G. HAMILTON.
